UNITED STATES PATENT OFFICE.

REUBEN E. OTTENHEIMER, OF BALTIMORE, MARYLAND.

REFRIGERATOR.

1,389,688.

Specification of Letters Patent. Patented Sept. 6, 1921.

Application filed November 11, 1920. Serial No. 423,237.

To all whom it may concern:

Be it known that I, REUBEN E. OTTENHEIMER, a citizen of the United States, residing at Baltimore city, State of Maryland, have invented certain new and useful Improvements in Refrigerators, of which the following is a specification.

This invention relates to refrigerators which are cooled by means of a refrigerant circulating through a coil, and its object is to provide improved means for automatically regulating the temperature in the provision or storage chamber.

The invention also has for its object to provide a very simple mounting of the circulating devices to permit the same to be easily installed in an ordinary household refrigerator.

With the objects stated in view, the invention consists in a combination and arrangement of parts to be hereinafter described and claimed, and in order that the same may be better understood, reference is had to the accompanying drawings forming a part of this specification.

In the drawings,

Figure 1 is a cross-section of the refrigerator; Fig. 2 is a cross-section thereof from the front to the rear; Fig. 3 is a horizontal section on the line 3—3 of Fig. 1, drawn to an enlarged scale, and Fig. 4 is a plan view showing a fragment of a drain trough.

Referring specifically to the drawings, the body 5 of the refrigerator is of conventional design, and it is provided with a provision or storage chamber 6 provided with the usual assembly of shelves. The storage chamber 6 occupies most of the interior of the body 5, and at the top of said chamber there is built into the body a cooling chamber 7 to take the place of the usual ice compartment. This cooling chamber is composed of front and rear walls 8 and a bottom 9 extending lengthwise between the side walls of the body 5. The walls 8 are spaced from the front and rear walls of the body 5. The bottom of the cooling chamber slopes in the direction of its longitudinal median line, as shown in Fig. 2. The top of the body 5 is provided with a tight-fitting removable cover 10 from the inner side of which the walls 8 are spaced at the top, so that the cold air in the chamber 7 formed by said walls and the bottom 9 may escape into the storage chamber 6.

In the chamber 7, over toward one end

thereof, is located a tank 11 adapted to hold a fluid refrigerant, such as brine. The top of the tank 11 has a depression to form a chamber 12 which is designed for the manufacture of small quantities of ice. The freezing chamber 12 is directly beneath an opening in the cover 10 so that access to said chamber may be had, and this opening is provided with a tight-fitting lid 13.

In the chamber 7 is also mounted a bank of coils 14 connected to the brine tank 11. A pump 15 is provided for circulating the brine through the coils 14, the pump being suitably connected to the latter for this purpose. The pump 15 is electric-motor driven, and it is mounted on the outside of the cover 10. The cover 10 also supports the brine tank 11 and the circulating coils, and hence the entire assembly can be readily installed, and is also removable from the body 5 by merely taking the cover 10 off.

At the longitudinal center line of the bottom 9 is a cold air outlet slot 16 which is provided with two oppositely slidable damper plates 17 extending parallel to the slot and located below the bottom 9. The damper plates may be spread or brought closer together, more or less, to control the escape of the cold air from the chamber 7 into the storage chamber 6 through the slot 16. The plates 17 are supported by guide cleats 18 carried by the side walls of the body 5.

In order to automatically control the damper plates 17 a thermostat 19 is provided, the same being located in the chamber 6 at the top thereof, and having a damper-operating rod 20 connected by toggle links 21 to the plates 17. It will therefore be seen that the movement of the thermostat in response to changes in the temperature within the chamber 6, causes the rod 20 to move in the direction of its length, whereby, through the toggle links 21, the damper plates 17 are spread or drawn together according to the direction the rod is moved by the thermostat. The thermostat may be one of ordinary design, and hence a detailed description thereof is not necessary.

The bottom 9 of the chamber 7, on each side of the slot 16, is provided with a drain trough 22. These two troughs have a downward slope from their ends or the sidewalls of the body 5 and are connected at their lowest portion, as shown at 23 in Fig. 4, and from said connecting portion leads a drain

pipe 24 which passes through the chamber 6 and through the bottom wall thereof as shown in Figs. 1 and 2, its outlet end being fitted with the usual trap 25. As shown at 5 26 in Fig. 3, the inner edges of the damper plates 17 are recessed to clear the drain pipe 24 where it connects with the connecting portion 23 of the troughs 22, and the rod 20 also has an offset portion 27 to clear the 10 drain pipe.

Above the troughs 22 is a deflector plate 27.

The pump 15 may be provided with a cover as shown dotted in Fig. 1.

I claim:

A refrigerator comprising a storage chamber, a cooling chamber at the top of the storage chamber and having a bottom outlet slot, a pair of oppositely movable damper plates associated with the slot, and 20 an operating rod extending lengthwise of the damper plates, toggle links connecting the rod to the respective damper plates, and a thermostat operatively connected to the rod. 25

In testimony whereof I affix my signature.

REUBEN E. OTTENHEIMER.
